UNITED STATES PATENT OFFICE

165,524

MODEL AIRPLANE

Letcher F. Johnson, Opelika, Ala.

Application June 20, 1949, Serial No. 3,416

Term of patent 14 years

(Cl. D34—15)

To all whom it may concern:

Be it known that I, Letcher F. Johnson, a citizen of the United States, residing in Opelika, county of Lee and State of Alabama, have invented a new, original, and ornamental Design for a Model Airplane, of which the following is a specification, reference being had to the accompanying drawing, forming a part thereof.

In the drawing:

Fig. 1 is a top plan view of the model airplane, showing my new design;

Fig. 2 is a front elevational view thereof;

Fig. 3 is a side elevational view thereof; and

Fig. 4 is a top perspective view thereof, the dotted line illustration of the engine and propellor being omitted for convenience of illustration.

In bottom plan view of the appearance of the airplane is substantially the same as in top plan view.

The dominant features of my new design are shown in solid lines in the drawing.

I claim:

The ornamental design for a model airplane, as shown and described.

LETCHER F. JOHNSON.
